UNITED STATES PATENT OFFICE.

THOMAS AMPHLETT, OF KIEV, RUSSIA.

WATER-GAGE AND ALARM.

SPECIFICATION forming part of Letters Patent No. 256,264, dated April 11, 1882.

Application filed November 2, 1881. (No model.) Patented in Germany May 27, 1880, in France August 2, 1880, in Belgium August 4, 1880, and in Austria September 27, 1880.

To all whom it may concern:

Be it known that I, THOMAS AMPHLETT, a subject of the Empire of Germany, residing at Kiev, in the Empire of Russia, have invented 5 new and useful Improvements in Water-Gages, of which the following is a specification.

This invention relates to certain improvements in water-gages and alarms connected therewith, the specific construction which constitutes my invention being fully set forth in the following specification.

In the accompanying drawings, Figure 1 shows a side elevation, Fig. 2 a vertical section, and Fig. 3 a horizontal section after line 15 *xx*, of my improved water-gage.

Similar letters indicate corresponding parts.

This gage principally consists of a float, A, made of sheet metal, connected at its top to a vertical rod terminating in a rack, B. This 20 rack gears into a cog-segment, C, fast upon a spindle, D, provided with a valve-seat, K, Fig. 3, by means of which it passes steam-tight through the front side of a case or cylinder, H, screwed upon the boiler, and through a 25 dial-disk, J, fastened onto said case H. On the end projecting on the outside of this dial the spindle D supports an indicator-hand, Z, intended to show by marks upon said dial the different levels of water in a boiler. With the 30 rising and falling of the water the float must rise and fall also, and with it rack B, acting upon segment C, which turns spindle D and hand Z to the right or left, according to rise or fall, so that the water-level can always be 35 told by the position of the hand to the marks on the dial.

The float-rod is provided with two collars, E, Fig. 2, so adjusted that they will, one on reaching its highest, the other on reaching its 40 lowest, point, move one of the two bell-crank levers F. One end of each of these levers is connected with a small valve, *v*, while the other terminates in a fork, through which the float-rod passes. When, in case of too high or too 45 low water, one of the collars E touches the upper or lower lever, F, it opens the respective valve, and a steam-whistle, *w*, connected with

it is put in action. G is a spring connecting the two lever-arms for the purpose of keeping the valves *v* closed. 50

For the cog-segment of the arrangement just described a plain segment without any teeth may be substituted, over whose circumference two light chains, wires, or strips of metal are passed, the ends of which are connected with the segment and with the float-rod, respectively—that is, the one chain, wire, or strip is fastened with one end to the top end of the float-rod and with the other to the opposite (lower) end of the segment, and vice 55 versa, as shown in Fig. 4 of the drawings.

In place of a segment, a crank or lever, as shown in Fig. 5, may be used to the same effect.

The principal advantages of this water gage or indicator over the common glass gages and 60 the magnetic float-gages are: the actuating of the alarm-whistle with the greatest precision, and permitting of a very exact control of the water-level even at a distance from the boiler. The latter object may easily be attained by 65 lengthening the spindle D to any desired distance—as, for instance, to engine-room or office, where a dial may be fixed, so as to permit observing the water-level from there without having to go to the boiler. 70

What I claim as new, and desire to secure 75 by Letters Patent, is—

In water-gages, the combination, with a float, of a steam-tight case or cylinder fast upon and communicating with the boiler, a spindle, 80 D, with hand Z, a dial, J, a rod extending from the float and connected to the spindle D, two collars, E, mounted on this rod, bell-crank levers F, valves *v*, and whistles *w*, all for the purpose, and substantially as described. 85

In testimony whereof I have hereunto set my hand in the presence of two subscribing witnesses.

THOMAS AMPHLETT.
